UNITED STATES PATENT OFFICE.

JOHN H. RICHARDSON, OF MELROSE, AND ALBERT E. HUDSON, OF BEVERLY, MASSACHUSETTS, ASSIGNORS TO UNITED SHOE MACHINERY CORPORATION, OF PATERSON, NEW JERSEY, A CORPORATION OF NEW JERSEY.

SOLE-FORMING MACHINE.

Original application filed July 9, 1919, Serial No. 309,555. Divided and this application filed November 28, 1922. Serial No. 603,821.

This invention relates to machines for use in the manufacture of shoes, the present application being a division of our co-pending application Serial No. 309,555, filed July 9, 5 1919.

An object of the invention is to provide a novel form of leveling device, which, without sacrifice of other utility, will be especially adapted for use in a relasting machine. From this point of view the invention comprises a beating or equivalent leveling device which is normally held in an idle position, to be out of the way during the 10 relasting operation, and which can be moved 15 against the sole of a bottomed shoe to operate thereon, as for example after the shoe has been relasted.

It is preferable that a device of this character should be driven only when in use, 20 and accordingly our invention contemplates the use of power-driven connections controlled by relative movement of a shoe and the device, as by throwing a clutch, so that the device operates only when in 25 engagement with a shoe. In the illustrated embodiment of the invention a beater is mounted on a manually-moved support adjacent a power-driven shaft, and mechanism arranged to be connected to the shaft by 30 movement of the support is provided for operating the beater. Preferably there is a latch to hold the support with the beater in operative position.

The above and other objects and features 35 of the invention, including specific constructions and novel combinations of parts, will be apparent from the following description of one embodiment of our invention illustrated in the accompanying drawings, in 40 which:

Fig. 1 is a side elevation of a relasting and leveling machine with parts of the machine in section and showing the last support in the position it occupies while the forward 45 part of the shoe is being pulled thereon;

Fig. 2 is a side elevation of the beater mechanism and the last support showing the latter in the position it occupies while the heel portion of the shoe is being pulled 50 thereon;

Fig. 3 is a somewhat diagrammatic cross-section on the line 3-3 of Fig. 1 showing certain clutch controlling mechanism; and

Fig. 4 is a section on line 4-4 in Fig. 2. In the drawings 10 denotes the main frame having a forwardly and upwardly extending portion 12. To the base of the main frame there is pivoted for universal motion at 14, 15 a post 16 to the top of which is hinged at 18 a last support 20 having a slidable pin 22 mounted therein to receive the last 24. The post 16 has an abutment surface 19, the purpose of which is to engage a similar surface 21 on the last support 20 and to serve as a stop for the latter when the last support 20 is swung about the pivot 18 to shoe-inverted position. In this position, the last support 20 forms, in effect, an extension of the post 16. Near the upper end of the post 16 is mounted a fork 26 to receive and support the heel end face of the last when positioned as indicated in Fig. 1. To hold the post 16 in fixed position while the forward portion of the shoe is being pulled on to the last there is provided a latch 28 provided with a pin having a tapered upper end 30 adapted to seat itself in a correspondingly shaped socket in arm 32 of the main frame. A spring 34 tends to thrust pin 30 into its socket from which it may be withdrawn by suitable mechanism, which, as exemplified in the drawings, consists of a pin 38 mounted in the lower end of the latch member and adapted to withdraw the same upon the operation of treadle 36. Pivoted to this treadle is a hook member 42 adapted to engage a pin 44 mounted in the main frame to hold the latch in its disengaged position. The upper end of this hook may be enlarged to provide a surface 46 adapted to be engaged by the toe of the operator to release the hook whereupon the treadle may be raised and the latch member 30 seated.

Turning now to the means for seating the 95 last in the forward portion of the shoe, there is provided a support 50 for the sole at the toe of the shoe carrying two blocks 52 of rubber or other suitable material to engage and grip the sides of the toe portion of the 100 shoe. This support 50 is pivoted at 54 to a rod 56 yieldingly held by spring 58 in a sleeve 60 at the lower end of which is formed a yoke 62 pivotally mounted on the main drive shaft 100. A roll 64 is provided at 105 the lower end of rod 56 and is held by spring

58 against a cam 66 so that upon rotation of the cam by means presently to be described the support 50 will be rapidly vibrated.

5 Pivoted to the sleeve 60 is an extensible link 67 provided with a compression spring 68 to yieldingly connect the toe support 50 with a gripper 70 pivoted to the main frame at 72 and provided with jaws 74 and 76 10 adapted to grip the heel portion of the sole of the shoe. Pivoted to the base of the main frame of the machine at 78 is a treadle 80 made in the form of a bell-crank lever and pivoted at its upper portion 82 to a link 86, 15 the latter being pivoted at 88 to one end of a U-shaped lever 90 pivoted at 92 to the main frame. The U-shaped lever 90 is pivoted at 93 to one end of a link 94 the other end of which is pivoted to the downwardly extending end of the pivoted jaw 76 20 of the gripper. The treadle 80 is normally held in its raised or inoperative position by means of a spring 96 connecting it with the main frame.

25 While the machine is at rest the support for the forepart of the shoe and the grippers occupy substantially the position indicated in dotted lines in Fig. 1. A last having been placed on the pin 22, and occupying 30 the position indicated in Fig. 1, the shoe is placed with the forepart of its sole on the toe support and the rear portion of the sole between the jaws of the gripper. The depression of treadle 80 operates first to close 35 the jaws of the gripper upon the sole of the shoe and then to swing the gripper downwardly and to the right, as viewed in Fig. 1. This downward swinging movement is transmitted by link 67 to the toe support, the 40 two co-operating to pull the shoe on to the last. The movement of the yoke 62 of the toe support about shaft 100 operates as will now be described, to throw in clutch mechanism which causes cam 66 to vibrate 45 the forward portion of the shoe to settle the same on the last.

50 Mounted on the main drive shaft 100 is a belt pulley 102 about which passes a belt 104 driven from any suitable source of power. Connected to shaft 100 is a pulley having 55 grooves to receive belt 106 and 108 which drive other operating parts of the machine presently to be described. On the depending portion of one of the arms of the yoke 62 (see Fig. 3) is an inclined or wedge surface 112 adapted upon the swinging of sleeve 60 to co-operate with a corresponding wedge surface 114 formed on a sleeve 116 rigidly mounted on pin 118. This pin 118 is 60 mounted for longitudinal movement in the main frame and is moved in the direction of wedge surface 112 by a compression spring 120. The yoke 121 formed on the sleeve 116 operates to control a clutch member 122 to 65 move the same towards and away from a

co-operating clutch member 124 formed integral with the cam 66. It will thus be seen that the movement of the toe support from dotted to solid line positions in Fig. 1 will operate to permit the sleeve 116 to be 70 slid to the left as viewed in Fig. 3 under the action of the spring 120 to throw the clutch 122, 124 into operation and consequently to vibrate the rod 56 and the toe support. 75

After the last has been inserted in the forepart of the shoe the last support is swung upwardly by the operator about pivot 18 to invert the same and the last is then rotated in a horizontal plane through 180° 80 to position it as indicated in Fig. 2.

Pivoted to the base of the main frame of the machine is a third treadle 130 to which is connected a rod 132. Supported at the upper end of this rod is a shoe horn comprising a pair of co-operating jaws 134 and 136 for gripping and pulling the shoe downwardly on to the last. The gripping portion of jaw 134, as indicated, is of more or less conventional shoe horn shape and is adapted 90 to be inserted inside of the shoe and to be pulled down between the upper and the last. Jaw 136, which may be a block of rubber or other suitable material, is pivoted to the bell-crank lever 138 which latter is pivoted 95 at 140 to the extremity of a handle portion 142 of the shoe horn. The other arm of the bell-crank lever 138 is pivoted to the extremity of the rod 132 which latter passes through an opening in an extension of the lower end 100 of the shoe horn. Rigid with the post 16 is an outstanding arm 144 provided with an elongated slot to movably hold the rod 132 in position.

Journalized in the post 16 is a shaft 150 105 on which is mounted clutch mechanism similar in all its essential characteristics to that of Fig. 3, and adapted to be thrown into and out of operation by the movement of an arm 152 through which passes rod 132, the 110 arm 152 being moved into and out of clutch engaging positions by means of collars 154 and 156 rigidly but adjustably mounted on the rod 132. A downwardly extending portion of the arm 152 carries a wedge surface, 115 a movement of which towards and from operative position controls the operation of a cam 158 in the manner explained in connection with Fig. 3. Engaging the cam 158 is a roll 160 mounted on a downwardly 120 extending yoke portion 162 of a rod 164, this latter being mounted for longitudinal vibrating movement in the post 16. To hold the roll 160 in engagement with the cam 158 there is provided a spring 170 connected at 125 one end to an eye 171 formed on the yoke 162 and at its other end to the post 16 at 172. The upper end of the rod 164 contacts with the lower end of the pin 22, when 130 in the position indicated in Fig. 2, to vibrate

the last in a direction transverse to the plane of the sole thereof to assist in settling the shoe on the last as the heel portion of the upper is drawn into position by the shoe 5 horn.

To assist in settling the shoe on the last and to shape the sole thereto there is provided a beater which may be thrown into and out of operation by means of a handle 10 180 pivoted upon a shaft 197 which is journaled in the upper portion of the main frame and is driven by means of the belt 108. The handle 180 is adapted to be locked in operative position by means of a sliding 15 pin 182, controlled by a pivoted lever 183, held in operative position by a spring 185, as clearly shown in Fig. 2. This beater comprises a rod 184 slidably mounted in a carrier or sleeve 186 and having a beating head 20 188 connected by a ball and socket joint 190 to its lower end. A spring 192 connected to the rod 184 and the sleeve 186 of the beater normally tends to hold the beater in its lowermost position relatively to the sleeve 186. 25 Clutch mechanism similar to that of Fig. 3 is provided for controlling the operation of the beater so that the same will be vibrated when moved into the position of Fig. 2, but will come to rest when the handle 180 is elevated by a suitable spring 207, as indicated in Fig. 1. For this purpose the handle 180 is provided with a wedge surface 194 co-operating with a wedge surface 196 of a clutch shifting yoke, the two controlling 30 35 the operation of a clutch mounted on the shaft 197, in the manner described in connection with Fig. 3. Mounted on the shaft 197 and controlled by this clutch is a cam 200 co-operating with a roll 202 for reciprocating the beater. The roll 202 is mounted on a link 204 shown in dotted lines in Figs. 1 and 2 and in cross-section in Fig. 4 pivoted at one end to the handle 180 at 181 and pivoted at the other end, as at 205, to the lower 40 45 end of the link 206. The upper end of the link 206 is pivotally connected to the stem 184 of the beater. The sleeve 186 of the beater is pivoted at 208 to projection 210 of the handle 180 and is also pivoted at its upper 50 55 end to a link 212 connecting it with the forward portion of the main frame of the machine. It will thus be seen that the rotation of cam 200 will rock the lever 204 about its fulcrum 181 and will thus reciprocate the link 206 and through it the beater.

In order to tension the belt 106 to the desired extent irrespective of the position of the post 16 a suitable belt tightener, indicated at 214, is provided.

60 While it is believed that the mode of operation of the machine will be clear from the above description it may, for purposes of convenience, be recapitulated as follows.

A last having been placed on pin 22 and 65 the same moved to the position of Fig. 1,

the forepart of the shoe is placed thereover so far as convenient by hand. At this time the toe support and the grippers for the heel portion of the sole occupy substantially the positions shown in dotted lines in Fig. 1. 70 The operator thereupon presses downwardly upon treadle 80 which first closes the jaws of the gripper 70 upon the heel portion of the sole of the shoe and thereafter moves the gripper and the toe support 50 rearwardly and downwardly to the full line position of Fig. 1, thus seating the last in the forepart of the shoe. As the support 50 is thus moved, cam 66 is operated to vibrate the toe support and the shoe to settle the last in 80 the shoe. Treadle 80 is now released whereupon spring 96 moves the gripper 70 and the toe support 50 back to the dotted line position of Fig. 1, leaving the last inserted in the forepart of the shoe. Handle 180 and the beater being in their elevated or inoperative position, the last is now swung forwardly and rotated horizontally to the position of Fig. 2. The shoe horn is now manipulated manually by 85 means of handle 142 to grip the rear portion of the upper of the shoe which has now to be pulled down into place. By means of treadle 130 the operator pulls the rear portion of the upper held by the shoe horn down 90 into place and at the same time the last is vibrated through rod 164, cam 158 and their actuating mechanism. During these operations post 16 is, of course, rigidly held in position by its latch mechanism. When the 95 last is nearly or completely inserted in the shoe the operator pulls down on handle 180 latching the same in the position of Fig. 2, whereupon beater 188 is vibrated to settle the shoe on the last. At this stage of the 100 operation by pressing downward on treadle 36 the operator releases the latch of the post 16 and thereafter moves the post from one position to another in order that the beater may shape and mold various portions 105 of the sole of the shoe as may be necessary. Handle 142 of the shoe horn at this stage of the operation forms a convenient means by which the operator may swing the post 110 from one position to another. 115

The above-described relating mechanism is not claimed herein, as it forms the subject-matter of our parent application No. 309,555. Other features of novelty not claimed herein, relating to the means for supporting and for vibrating the last, are claimed in our divisional application, Serial No. 251,438, filed Feb. 2, 1928. 120

While one embodiment of the invention has been described, it is not our intention to limit its scope thereby or otherwise than by the terms of the appended claims. 125

Having described our invention, what we claim as new and desire to secure by Letters Patent of the United States is: 130

1. A machine of the class described having, in combination, a beater, a handle for moving the beater into and out of operative position, means for reciprocating the beater, and means constructed and arranged to actuate the beater reciprocating means when the handle is operated to move the beater into operative position.

2. A machine of the class described having, in combination, a beater, a handle for moving the beater into and out of operative position, means for reciprocating the beater, means for latching the handle in beater reciprocating position, and means constructed and arranged to actuate the beater reciprocating means when the handle is operated to move the beater into operative position.

3. A machine of the class described having, in combination, a beater, a handle for moving the beater into and out of operative position, mechanism for reciprocating the beater, and a clutch constructed and arranged to actuate the beater reciprocating mechanism when the handle is operated to move the beater into operative position.

4. A machine of the class described, having, in combination, a last support, a beater for operating upon a shoe supported thereon, a handle for moving the beater into and out of operative position, means for reciprocating the beater, and means constructed and arranged to actuate the beater reciprocating means when the handle is operated to move the beater into operative position.

5. A machine of the class described having, in combination, a last support, a beater for operating upon a shoe supported thereon, a handle for moving the beater into and out of operative position, means for reciprocating the beater, and a clutch constructed and arranged to actuate the beater reciprocating means when the handle is operated to move the beater in operative position.

6. A machine of the class described having, in combination, a normally-idle beating device, a power-driven shaft, means rotatable about said shaft for relatively moving said device and a shoe to bring the device against the shoe, and power mechanism controlled by said means for operating the device.

7. A machine of the class described having, in combination, a normally-idle beating device, a power-driven shaft, mechanism for operating said device, a clutch for connecting the mechanism to the shaft to be operated thereby, and means rotated about said shaft by relative movement of a shoe and said device to bring the device against the shoe for closing the clutch to operate the beater.

8. A machine of the class described having, in combination, a shoe support, a reciprocatory beater, a power-driven shaft,

operating connections between the beater and the shaft, and means controlled by relative bodily movement of the support and beater for connecting the beater to the shaft to be reciprocated thereby when in position to beat a shoe on the support.

9. A machine of the class described having, in combination, a shoe support, a beater, a power-driven shaft, mechanism for operating the beater including a clutch on the shaft, means controlled by relative movement of the support and beater for closing the clutch to operate the beater, and a spring tendency to operate said means to open the clutch.

10. A machine of the class described having, in combination, a beater, a power-driven shaft, means rotatable about said shaft to move the beater against the shoe, and a device operated by movement of the beater by said means to connect the beater to the shaft to be operated thereby.

11. A machine of the class described having, in combination, a pivotally-mounted reciprocatory shoe-engaging device, a power-driven shaft, and a manually-controlled lever for pivotally rocking said device to bring it against the shoe and for simultaneously connecting it to the shaft to be reciprocated thereby.

12. A machine of the class described having, in combination, a pivotally-mounted support, a shoe-shaping tool movably mounted thereon, a power driven shaft, tool-operating connections including a cam loosely mounted on the shaft, and means operated by movement of the support for connecting the cam to the shaft to operate the tool when it is moved against a shoe by the support.

13. A machine of the class described having, in combination, a pivotally-mounted support, a shoe-shaping tool movably mounted thereon, a power driven shaft, tool-operating connections including a cam loosely mounted on the shaft, means operated by movement of the support for connecting the cam to the shaft to operate the tool when it is moved against a shoe by the support, and a manually-controlled device to hold the support in idle position with the cam loose on the shaft or to rock the support to bring the tool against a shoe and connect the cam to the shaft.

14. A machine of the class described having, in combination, a shoe beater, a power-driven shaft, a manually movable member rotatable about said shaft, and connections from the shaft for operating the beater, said connections including a clutch controlled by movement of said rotatable member.

15. A machine of the class described having, in combination, a reciprocatory shoe beater, a power-driven shaft, a cam on said shaft, connections from the cam to the beater

for operating the beater, and manually-controlled means for connecting and disconnecting the shaft and the cam.

16. A machine of the class described having, in combination, a shoe beater, a power-driven shaft, a cam and connections therefrom for operating the beater, the cam being loosely mounted on said shaft, and a manually-controlled clutch for connecting the 10 cam and the shaft.

17. A pounding machine for use in operating on shoes after the soles have been attached comprising, in combination, a hammer member, a spring urging said member 15 against the work, and mechanism alternately to draw said member back and then release it suddenly to the action of the spring, thereby to impart to the hammer member a rapid succession of yielding per- 20 cussional impulses.

18. A pounding machine for use in operating on shoes after the soles have been attached comprising, in combination, a hammer member, a spring urging said member 25 against the work, a cam having a portion gradually to pull said member back against the tension of the spring and a sudden drop beyond said portion to release the hammer member to the action of the spring, and 30 power mechanism to move said cam at a substantial speed to impart to the hammer member a rapid succession of yielding per- cussional impulses.

19. A machine of the class described comprising, in combination, a shoe-beating device, means normally to hold said device in an idle elevated position, and a latch to hold the device in operative position.

20. A machine of the class described comprising, in combination, a shoe-beating device, a swinging support to hold said device in idle position, the support being manually movable to bring the device to operative position, and a latch to hold the support with 45 the device in operative position.

21. A leveling machine comprising, in combination, a device to beat the outsole of a bottomed shoe to conform it to a last in the shoe, a support for the last and shoe, 50 the beating device and the support being

relatively movable both laterally and longitudinally of the shoe to beat the entire area of the sole, and means for moving the beating device to and from position to operate upon the sole.

55

22. A leveling machine comprising, in combination, a power-driven device to beat the outsole of a bottomed shoe to conform it to a last in the shoe, and a universally-swinging support for the last and shoe, the 60 support being movable to carry the shoe both laterally and longitudinally past the beater, and the beating device being movable bodily to and from position to operate upon the shoe.

65

23. A machine as defined by claim 22, in combination with a latch to hold the support rigidly in a vertical position or to be released to allow the support to be swung as described.

70

24. A machine of the class described having, in combination, a normally idle beater, a carrier for the beater, yielding means normally operative to hold the beater carrier retracted from position to enable the beater 75 to operate upon the bottom of a shoe, a device for moving the beater carrier into position for such operation of the beater, power-supplying mechanism for reciprocating the beater, and means controlled by the movement of the beater carrier into said position for actuating the beater reciprocating means.

80

25. A machine of the class described having, in combination, a normally idle beater, a carrier for the beater, yielding means normally operative to hold the beater carrier retracted from position to enable the beater to operate upon the bottom of a shoe, a device for moving the beater carrier into position for such operation of the beater, power-supplying mechanism for reciprocating the beater, and means including a power-driven shaft and a clutch controlled by the movement of the beater carrier into said position for reciprocating the beater.

85
